(57) **CLAIM**

The ornamental design for a packing machine, as shown and described.

DESCRIPTION

FIG. 1 is a front perspective view of a packing machine in accordance with the design;

FIG. 2 is an enlarged portion of the rear perspective view of the packing machine in FIG. 1;

FIG. 3 is a detailed portion of the front perspective view of the packing machine in FIG. 1;

FIG. 4 is a detailed portion of the rear perspective view of the packing machine in FIG. 1;

FIG. 5 is a left side plan view of the packing machine in FIG. 1;

FIG. 6 is a right side plan view of the packing machine in FIG. 1;

FIG. 7 is a front plan view of the packing machine in FIG. 1;

FIG. 8 is a rear plan view of the packing machine in FIG. 1; FIG. 9 is a top plan view of the packing machine in FIG. 1; and,

FIG. 10 is a bottom plan view of the packing machine in FIG. 1.
